[57] CLAIM

The ornamental design for a toy glider, substantially as shown and described.

DESCRIPTION

FIG. 1 is a perspective view of a toy glider showing my new design;

FIG. 2 is a top plan view thereof, the side opposite being substantially a mirror image;

FIG. 3 is a right side elevational view thereof, the side opposite being substantially a mirror image; and,

FIG. 4 is a front elevational view thereof.
